UNITED STATES PATENT OFFICE.

ANTON N. HORNUNG, OF LOS ANGELES, CALIFORNIA.

REFRIGERATOR-COUNTER DISPLAY-CASE.

1,347,161.

Specification of Letters Patent. Patented July 20, 1920.

Application filed November 11, 1919. Serial No. 337,254.

To all whom it may concern:

Be it known that I, ANTON N. HORNUNG, a citizen of the United States, residing at 1438 W. 37th Drive, in the city of Los Angeles, county of Los Angeles, and State of California, have invented a new and useful Refrigerator-Counter Display-Case, of which the following is a specification.

This invention relates to furniture or fixtures for butcher shops, fish markets and the like, in which the dealer stands behind the goods and the customer in front of them, and an object is to present the goods to the customer in a direct and favorable way, to allow the dealer to see the goods equally well with the customer and to have direct access to the goods with minimum loss of refrigerant, and to allow most ready and direct access to the refrigerator when such access is required.

An object of this invention is to provide for the display of meats and other products requiring refrigeration, a superior show case adapted to the purpose in a superior manner and to make provision for introducing the refrigerant with great convenience and without disturbing the arrangement of the products displayed.

An object is to provide a show case of this character having an attractive appearance and especially adapted to be kept in thoroughly sanitary condition.

Another object is to make provision whereby simplicity and cheapness of construction are combined with facility of access to the refrigerated products with minimum loss of refrigerant.

A feature of the invention resides in a construction wherein a single outside door may give access to a common receptacle, in which both the refrigerant and the products to be refrigerated and displayed are contained, and yet to allow the door to be opened and closed, to allow the dealer to place and to withdraw the products with any desired frequency without serious loss of refrigerant.

Other features relate to special construction and arrangement, whereby cheapness of construction and ease of removal of parts, for cleansing, and to give access to the interior for the purpose to which the same is adapted, is secured.

The invention is particularly adapted to

show cases refrigerated with ice as the refrigerant, and is broadly new and basic in that its frame is practically a two piece structure, one of the pieces being constructed to give the counter appearance and the other piece constituting the receptacle in which the ice and the products to be displayed are accommodated; the latter piece being supported by and partly chambered in the counter piece.

An object is to facilitate the construction, handling, transportation, and setting up of the refrigerator counter display case and to this end the device is made in a counter section and a display section adapted to be fitted together and detachably secured to each other by screws or other convenient detachable fasteners so that the device may be handled separately or in one piece as may be desired.

Features of the invention are applicable irrespective of whether the interior of the device is made accessible through only one or through a plurality of orifices or whether one or more than one closure be depended on to close entrance to such interior.

The invention may be embodied in different forms, and an important advantage gained in the preferred construction of the fixture, is the provision for ready admission into the refrigerator and display receptacle of cakes of ice that are somewhat larger than usual, without removal of any of the parts of the fixture.

This is secured by making the height of the entrance, coextensive or nearly so with that of the entrance to the receptacle and providing a shiftable and detachable support for the rear edges of the wire screens or grids that usually sustain the display above the ice; so that if the lumps of ice are somewhat too large to be inserted below the support, such support may be shifted without removal to enable the lumps of ice to be inserted; or, if it is desired to insert large cakes of ice and to place a display directly on such cakes, this may be accomplished by removing the grids and the grid support thus leaving the display and refrigerating receptacle free from any partition and also leaving the entrance free from any obstruction.

The shiftable and detachable grid support is preferably in the form of an angle-

iron carried by pins that are supported by uprights of the fixture.

Other objects, advantages and features of invention may appear from the accompanying drawings, the subjoined detailed description and the appended claims.

The accompanying drawings illustrate the invention.

Fig. 1 is a perspective view of a refrigerator display counter constructed in accordance with this invention. Portions of the pedestal and refrigerator are broken away for clearness of illustration.

Fig. 2 is a cross section of the same adapted to illustrate various features of construction.

Fig. 3 is an enlarged fragmental section illustrating details of construction at the back of the counter. Line x^3 , Fig. 4, indicates the line of section.

Fig. 4 is a fragmental elevation of the supporting rail and the supplementary closure shown in Fig. 3.

Fig. 5 is a fragmental perspective view of the back of the counter, two of the doors being open, one of the supplementary closures being removed and one of the mullions shown detached.

Fig. 6 is a broken longitudinal mid-sectional elevation looking rearwardly from the middle of the counter toward the back doors, omitting the grid.

Fig. 7 is a fragmental detail on an enlarged scale of the floor of the case.

The display counter is a two piece article of furniture in that it comprises a hollow pedestal 1, constituting the counter section and a display case 2, which is seated inside the pedestal and extends above and below

the cornice 3 thereof. Said display case constitutes the cold box and is transparent above, and opaque below, said cornice. The pedestal comprises a base 4, dado 5, and the cornice 3 in front; and said base, dado, and

cornice may extend around the front side and one or both ends of the pedestal. The rear side of the pedestal is preferably open, as indicated at 6 and is provided below the top of the pedestal with a rail 7 extending

from end wall to end wall of the hollow pedestal. The base is made up of a floor piece 8, sills 9 and molding 10. The cornice 3 may be a strip of wood extending along the top of the dado 5 at the front side and both ends of the pedestal top. The case 2 has an external intermediate molding 11 and extends down into the hollow pedestal and is supported by the molding 11 which rests on the top of the pedestal and practically serves

to complete the cornice 3. The portion of the case which is submerged in the top of the pedestal when the parts are assembled, is made of heat insulating material and constitutes a refrigerant receptacle 12 for the cold box or case 2. It has a heat insulating

floor 13, and is shown provided with a refrigerant rack 14 upon which ice, not shown, may be supported. Near the top of the refrigerant receptacle 12, a support in the form of cleats 15 is fixed to the inside of the front and end walls 16, 17 of the refrigerant receptacle. A grid 18 formed of one or more sections of wire screen is mounted at the top of the refrigerant receptacle and is mainly supported by the cleats 15; such support extending around inside the front and end walls of said box.

The portion of the case which is above the cornice piece 11, when the counter is assembled, is mainly composed of transparent plates suitably connected together to form the front wall 19, end walls 20, top 21, and the rear construction connecting the floor of the refrigerant receptacle 12 and the display compartment thereabove which is formed by said transparent plates and their connections. The transparent plates may be made of any suitable material, and are preferably of plate glass. Above the rear rail 7 of the pedestal there is a frame constituting a part of the display case and composed of the heat insulating floor 13, front wall 16 and end walls 17, the bottom bar 22, the stiles 23, the top bar 24, and mullions 25 and 25'. Said top bar and stiles are joined to the rear edges of the top and end plates of the display case. The mullions, may be detachably connected to the bottom and top bars 22 and 24 between the stiles 23. One of the mullions 25 is shown detached and laid on top of the display case in Fig. 5, and another mullion 25' is shown fixed in place. The doors 26 are pivotally mounted as by suitable hinges 27 on the stiles and mullions as the case may be, and in the form shown in Fig. 5, the two doors close upon the two bars and the detachable mullion 25, when said mullion is in place.

Detachable means are provided to support the rear edge of the grid and such means are shown as a right-angle rail 28, the upright limb 29 of which is provided with key-holes 30. Said rail is supported by screws 31, the heads of which may pass through the larger portion of the key-hole, the smaller portion of said key-hole being at the top to accommodate the stem of the screw when the angle-iron rail is hung on the screw as indicated in Figs. 3 and 4.

The lower limb 32 of the angle iron projects horizontally to support the grid or grating 18.

The case at the top of the fixture constitutes a refrigerating receptacle and the same is divided into upper and lower compartments by the grid 18 which may be of woven wire or other material allowing free circulation of air up and down therethrough.

The angle-iron rail comprising limbs 29 and 32, marks a dividing line at the rear of

the case between the upper and lower compartments of the refrigerating display case; and the doors 26 extend above and below said line, so that when one or more of the 5 doors are opened, access through the opening formed by the bottom and top bars 22 and 24 and the stiles and mullions 23 and 25, 25', is given to the outside air. Supplementary closure means in the form of aprons 10 made of sheet metal or other suitable material and having their upper edges bent to form hook members 35, hook over the upper edge of the upright limb 29 of the angle rail, and hang down therefrom. One of these 15 aprons is provided for each of the spaces below the grid, which are normally closed by the doors; and when said aprons are hung in place, they form closures to prevent cold air from flowing out of the compartment. 20 In practical use the case will be charged by opening the doors 26; and if desired the mullion 25 may be removed and the aprons 34 will also be removed. This gives access to the lower compartments beneath the grids 25 to allow ice to be inserted thereinto; then by replacing the mullion 25 and the aprons 34, the cold air is prevented from flowing out over the edge of the bar and is thus practically kept from flowing out of the 30 lower compartment. The articles such as meat and other perishable products that are to be displayed in the case will then be put upon the grids and then with the mullion 25 in place, the refrigerator doors 26 will be 35 closed and locked or otherwise made fast in the usual way. In this way the refrigerating case presents to the customer the appearance of a transparent show case on the top of a counter and the show case serves 40 the purpose of the counter. The goods to be preserved are in this way visible and can be kept in attractive form and when it is desired to cleanse the interior, this can be readily done by removing the grids, the rail, 45 and the ice rack; whereupon the parts may be thoroughly cleaned.

The construction shown may be fixed together by any suitable fastenings as the screws 36 through the pedestal 1 into the box 50 which forms the lower part of the display case. The lower rail 22 at rear of the case is reinforced along its horizontal surface, with a piece of strap-iron, 37, which protects it against damage by ice during the filling of 55 the ice receptacle 12.

The pedestal and the show case are manufactured independently of each other and are arranged to be fastened together as indicated for use, and they can be separated 60 from each other for storage or transportation.

It is understood that the closure means may be variously constructed and that the outside closure may be made in one or more 65 than one hinged pieces in any form desired

and may or may not be provided with panels or plates 38 of translucent or transparent material.

The insulating floor is shown constructed of wooden layers *a*, *b*, *c*, and cork layers *d*, *e*, 70 and an inner sheet of metal *f*, and may be otherwise constructed as may be decided upon.

The drip-pipe *g* may be constructed and located as desired and may be connected 75 with any suitable drain.

The keyholes 30 are elongated up and down, thus allowing the portable angle-iron rail 28 to be shifted up to let ice pass, and the heads of the pins formed by screws 31 80 prevent withdrawal except when the heads register the larger opening of the keyhole.

I claim:

1. A refrigerator display counter comprising a counter section; a receptacle seated in 85 the top of said section; a grid separating the receptacle into upper and lower compartments, the lower compartment being located below the level of the top of the counter section, and the upper compartment being 90 adapted to display the contents of the upper compartment; one side of said case being provided with an opening communicating with both compartments thereof; closure means to close said opening, and supplementary means for closing the lower compartment while said closure means are open to give access to the upper compartment.

2. In a fixture of the character set forth, the combination with a display case having 100 an entrance at the rear, and interior grid supporting means and a grid inside said case; of a rail adapted to support the rear edge of the grid, and means to detachably support said rail at a plane between the top 105 and bottom of the entrance to coöperate with the interior grid supporting means.

3. In a fixture of the character set forth, the combination with a display case having an entrance at the rear, and interior grid 110 supporting means and a grid inside said case; of a rail adapted to support the rear edge of the grid; means to detachably support said rail at a plane between the top and bottom of the entrance to coöperate with the 115 interior grid supporting means, and apron means detachably supported by said rail to close the entrance below the level of the grid.

4. In a fixture of the character set forth, a pedestal, a display case partly submerged 120 in said pedestal and having an entrance at the rear and an upright frame at such entrance, headed pins in said frame and rails provided with holes by which the rail is shiftably hung on the pins.

5. A display case provided with an entrance at one side, a rail extending from end to end of the entrance; an apron formed of a sheet and adapted to catch upon the rail and to close the portion of the entrance that 125

is below said rail; and a door to close said entrance.

6. A two piece ice containing refrigerator counter display case fixture provided with a 5 wire shelf, the case portion below the wire shelf being submerged into the counter portion; said fixture having doors which expose both the display and the ice, and having a portable angle-iron on the door side 10 to support the shelf, and also having remov-

able aprons carried by said rail and covering the door opening portion beneath the angle-iron.

In testimony whereof I have hereunto set my hand at Los Angeles, California, this 1st 15 day of November, 1919.

ANTON N. HORNUNG.
